US00D715479S

(12) **United States Design Patent**
Johnston(10) **Patent No.:** **US D715,479 S**
(45) **Date of Patent:** **** Oct. 14, 2014**(54) **LIGHT-GENERATING SYSTEM**

- (71) Applicant: **John F. Johnston**, Paris (CA)
- (72) Inventor: **John F. Johnston**, Paris (CA)
- (**) Term: **14 Years**
- (21) Appl. No.: **29/435,712**
- (22) Filed: **Oct. 26, 2012**
- (51) LOC (10) Cl. **26-99**
- (52) U.S. Cl. USPC **D26/113; D26/118**
- (58) **Field of Classification Search**

Primary Examiner — Garth Rademaker*Assistant Examiner* — LLorelys Martinez-Rivera(74) *Attorney, Agent, or Firm* — McCarter & English LLP(57) **CLAIM**

The ornamental design for a light-generating system, as shown and described.

DESCRIPTION

FIG. 1 is a perspective view of a light-generating system showing the present invention;

FIG. 2 is a right elevational view thereof;

FIG. 3 is a left elevational view thereof;

FIG. 4 is a top plan view thereof;

FIG. 5 is a bottom plan view thereof;

FIG. 6 is a front elevational view thereof; and,

FIG. 7 is a rear elevational view thereof.

The broken lines in the figures show structure or boundaries that are not part of the claimed design.
